INKING MECHANISM

Commodore D. Ryan, Los Angeles, Calif., assignor
to National Postal Meter Company, Los Angeles, Calif., a corporation of California

Application January 18, 1933, Serial No. 652,255

10 Claims. (Cl. 101—335)

This invention relates to printing presses, and particularly to printing presses of the reciprocating or oscillating type.

While the invention may be used for many different tasks of printing it is especially adapted for use in a metered mailing machine, the function of which is to print postage stamps on letters, cards, small packages, and the like, and to count the amount of postage thus printed and lock itself against further use when a predetermined amount of postage purchased from the post office has been used up. Accordingly a preferred embodiment of my invention is disclosed herein as associated with a metered mailing machine.

It is especially desirable that metered mailing machines operate over considerable periods with a minimum of attention. One of the features of mailing machines which has given trouble to users in the past is the means for inking the printing die.

It is an object of my invention to provide an inking means for a metered mailing machine which will operate satisfactorily over long periods of time without attention.

The more specific objects of my invention include the following: to provide a die inking pad, the stamping surface of which may be readily renewed at small expense when worn out; to provide means for pressing the pad against the die in a manner to cause as little wearing of the pad as possible; to provide a means for feeding ink to the pad to keep this freshly supplied with ink at all times when the machine is running and yet prevent feeding of ink when the machine is not printing; to provide an ink reservoir and feeding means which will neither leak nor clog; and to provide an inking means which will apply ink uniformly and freshly to the printing die just before each impression.

Further objects and advantages will be made manifest in the following description, taken in connection with the accompanying drawings, in which:

Fig. 1 is a perspective view of a metered mailing machine with which the printing press of my invention is adapted to be used.

Fig. 2 is a perspective view of the printing press detached from the mailing machine shown in Fig. 1, the housing being removed.

Fig. 3 is a perspective view of one of the parts of the unit shown in Fig. 2.

Fig. 4 is an enlarged, longitudinal sectional view taken on the line 4—4 of Fig. 1.

Fig. 5 is a vertical sectional view taken on the line 5—5 of Fig. 4.

Fig. 6 is a horizontal sectional view taken on the line 6—6 of Fig. 4.

Fig. 7 is a sectional view similar to Fig. 6, certain parts thereof being broken away.

Fig. 8 is an elevational view of the structure shown in Fig. 3.

Fig. 9 is an operation view of the structure disclosed in Fig. 10.

Fig. 10 is an enlarged, fragmentary, vertical sectional view taken on the line 10—10 of Fig. 8.

Fig. 11 is an enlarged, fragmentary, vertical sectional view taken on the line 11—11 of Fig. 8.

Fig. 12 is a perspective view of an ink pad included in my invention.

Fig. 13 is a perspective view of the pad shown in Fig. 12, showing the manner of separating the two main parts thereof.

Fig. 14 is an enlarged, sectional view taken on the line 14—14 of Fig. 12.

Fig. 15 is a sectional view similar to Fig. 4 showing a different position of the parts disclosed therein.

Fig. 16 is a vertical sectional view taken on the line 16—16 of Fig. 17.

Fig. 17 is a semi-diagrammatic view of a portion of the structure shown in Fig. 15.

Fig. 18 is a sectional view similar to Figs. 4 and 15 showing another position of the parts disclosed therein, and

Fig. 19 is a vertical sectional view taken on the line 19—19 of Fig. 18.

Referring specifically to the drawings, a metered mailing machine 10, comprising a preferred embodiment of my invention, is shown in Fig. 1, this machine including a power unit 11 and 35 a detachable printing and metering head 12.

The power unit

The power unit 11 includes a housing 13, a hopper 14, a feeding and stripping mechanism 40 15, a conveyor 16, and a moistener 17.

Within the housing 13 of the power unit 11 is a motor and suitable power transmitting mechanism (not shown) for driving the various units of the machine 10 to be described hereinafter. The hopper 14 is mounted at one corner of the housing 13 for receiving stacks of envelopes, cards, and the like. The feeding and stripping mechanism 15 located adjacent the hopper 14 feeds 50 single envelopes from the hopper 14 onto the conveyor 16, the latter being adapted to carry these envelopes to the printing and metering head 12 and then discharge them from the machine. The moistener 17 is positioned so as to engage the 55

flaps of the envelopes as the latter are being conveyed from the hopper 14 to the printing head 12.

The printing and metering head

5 Referring particularly to Figs. 2 and 4, the printing and metering head 12 includes a frame 20, a printing mechanism 21, an inking mechanism 22, a power transmitting mechanism 23, and a meter 24.

10 The frame 20 includes a bottom 26 and an end plate 27, as shown in Fig. 4, the bottom 26 having a pair of grooved pins 28 normally received by suitable holes in the housing 13 of the machine 10. The printing head 12 is removably secured 15 to the housing 13 by a manually operated latch 29 pivotally mounted within the housing 13 and adapted to engage the grooves of the pins 28 as shown in Fig. 4.

15 Formed integral with the bottom 26 of the frame 20 is a pair of upstanding brackets 31, as shown in Figs. 4 and 6. Provided on the end plate 27 of the frame 20 is a bearing 32. Fixed to opposite sides of the bottom 26 is an upstanding yoke 33 which has bearing 34 mounted thereon, it being noted in Fig. 4 that the bearing 34 is 25 aligned with the bearing 32 of the end plate 27.

The printing mechanism

30 The printing mechanism 21 includes an oscillating printing member 36 and a platen 37, the latter being resiliently mounted on the bottom 26 of the frame 20 on suitable springs 38. The printing member 36 includes a pair of arms 40, these being pivotally mounted at one end thereof 35 on a pin 41, the latter being supported on the end plate 27 by suitable lugs 42 as shown in Fig. 4. The free ends of the arms 40 are joined by a cross member 43, to the under side of which a suitable printing die 44 is fixed. The member 36 40 is urged to its uppermost position by springs 45 positioned under the arms 40, one of these springs being shown in Fig. 2.

45 Fixed to the upper side of the cross-member 43 of the arms 40 is a pair of cam plates 46 and 47, these being formed as shown in Figs. 2, 4, and 5.

The inking mechanism

50 The inking mechanism 22 includes an oscillating member 50, an ink reservoir and applicator 51, and an ink pad 52. The oscillating member 50 includes a pair of arms 53, these being pivotally mounted on the aforementioned pin 41 as shown in Fig. 4. The arms 53 are joined at their ends 55 by a cross-member 54, a second cross-member 55 being provided adjacent the pivoted ends of the arms 53. Compression springs 56 are positioned under the cross-member 55 so as to urge the arms 53 upward as shown in Figs. 2 and 4.

60 Fixed at its ends to each of the arms 53 is a central cross-member 60, the latter having an enlarged portion 61 at its center. The portion 61 has a pin 62 fixed therein on a transverse axis and extending laterally therefrom. Below the pin 62 is a second pin 63 on a longitudinal axis, this pin carrying a roller 64.

65 The ink reservoir 51 is fixed to the arms 53 of the oscillating inking member 50 by side plates 66, as shown in Figs. 2 and 3. The reservoir 51 includes a tank 65 formed as shown to provide a central opening 65a. Formed on the lowermost edge of the tank 65 is a semi-cylindrical cavity 66a, as shown in Figs. 8, 9, and 10. Loosely rotatable within the cavity 66a is a roller 67, suitable holes 68 being provided in the wall of the

cavity 66a so as to allow ink to flow from the tank 65 onto the roller 67. Provided on one side of the lower end of the tank 65 at one end of the cavity 66a is a block 69 as shown in Figs. 3 and 8, this block having a strap 70 fixed thereto which is fixed to one of the arms 53 as shown in Figs. 7 and 8 so as to support the block 69 in proper relation with the lower end of the tank 65 so as to enclose one end of the cavity 66a.

5 The tank 65 is adapted to be filled through an opening 71 shown in Fig. 11, this opening being internally threaded to receive a plug 72. Formed integral with the plug 72 is a projection 73 having a vent hole 74 extending therethrough. The projection 73 is enclosed by a cup 75 which has openings 76 provided on its upper end. The cup 75 prevents the spilling of ink through the vent hole 74.

10 Slidably mounted between the arms 53 of the oscillating member 50 adjacent the cross-member 20 54 is a plate 80, opposite ends of the latter being received by suitable ways 81 provided on the inside of the arms 53 adjacent the lower edges thereof as shown in Figs. 4 and 7. A portion of the plate 80 is bent downward to provide a vertical portion 82, this having a bifurcated lug 83 fixed on the rear side thereof as shown in Fig. 4. Fixed on the upper surface of the plate 80 is a second plate 85, one edge of which is upturned to form a lip 86. Fixed to the plate 85 opposite the lip 86 is a spring finger 87 shown in Fig. 7.

15 The plate 80 is adapted to be reciprocated between the arms 53 in response to oscillation of these arms by means of a lever 90 shown in Fig. 4. This lever is pivoted adjacent its upper end on a pin 91, the latter being supported by the brackets 31 of the frame 20. The upper end of the lever 90 has a slot 92 which engages the aforementioned pin 62 in the enlarged portion 61 of the cross-member 60. The lower end of the lever 90 is joined to the lug 83 of the plate 80 by a link 93.

The inking pad

20 The inking pad 52, shown in Figs. 12 to 14, includes a base slide 100 and a replaceable ink pad 101. The slide 100 includes a pan 105 which has side walls 106 and 107 and end walls 108 and 109. Formed in the walls 108 and 109 are holes 110. The wall 108 has a notch 111 and a threaded hole 113, a notch not shown being provided in the opposite end wall 109. Positioned in the pan 105 is a felt pad 114. Resting on the pad 114 is a pair of springs 115. Permanently assembled with the pan 105 is a plate 116 which has fingers 117 at its ends, these fingers being received by the holes 110 in the end walls 108 and 109 of the pan 105. The springs 115 urge the plate 116 away from the pan 105 so that the fingers 117 are normally disposed at the top of the holes 110. Formed longitudinally in the plate 116 are downward extending ridges 118 and 119, it being noted in Fig. 14 that the ridge 119 is deeper than the ridge 118. Downstruck from the plate 116 is a pair of ears 120 for the purpose of positioning one of the springs 115.

25 The replaceable ink pad 101 includes a pan 124 comprising a floor plate 125 having side walls 126, outer portions of which are bent downwardly to provide flanges 127, as shown in Fig. 15. Provided in the pan 124 is a felt pad 132 over which a cover cloth 133 is fixed, the ends of the latter being secured to the pan 124. The cloth 133 is held in place on the pan 124 by an assembly plate 134, the latter having outstruck lugs 135 and a ridge 136 provided thereon as shown in Fig. 15.

- The replaceable ink pad 101 is assembled by folding the side portions of the cloth 133 tightly over the flanges 127 of the pan 124, moving the assembly plate 134 upwardly into position between the flanges 127 as shown in Fig. 14, and then bending the flanges 127 of the pan 124 inwardly so that the cloth 133 is firmly clamped between these flanges and the assembly plate 134.
- The replaceable ink pad 101 is placed upon or removed from the base slide 100 by sliding the outruck lugs 135 over the edges of the plate 116 as shown in Fig. 13. It is desirable that the ink pad 101 go on the base slide 100 in one position only, this being assured by the provision of the ridge 136 on the assembly plate 134 which prevents the pad 101 being placed on the base 100 in any other way than with the ridge 136 passing through the notch 111 into the channel 121 provided by the ridge 119 of the plate 116.
- The inking pad 52 is positioned in the printing head 12 of the machine 10 as shown in Figs. 4 and 7, it being noted that the base slide 100 of the pad 52 rests on the plate 85 between the lip 86 and the spring finger 87.

The power transmitting mechanism

The power transmitting mechanism 23 of the printing and metering head 12 includes a driven shaft 140 rotatably mounted in the aligned bearings 32 and 34 of the end plate 27 and yoke 33 respectively of the frame 20. The shaft 140 is driven from a shaft 141 of the power unit 11 through a flexible coupling 142 as shown in Fig. 4.

Fixed to the end of the shaft 140 adjacent the bearing 34 is a crank 143 having a crank pin 144 fixed thereto, a roller 145 being provided on the pin 144. As shown in Figs. 2, 4, and 5, the roller 145 of the crank 143 is disposed directly over the cam plates 46 and 47 of the cross-member 43. Also fixed on the shaft 140 adjacent the bearing 34 is a cam 146 shaped as shown in Fig. 17, this cam being positioned over and in contact with the aforementioned roller 64 of the pin 62 as shown.

Fixed to the shaft 140 between the bearings 32 and 34 are gears 147 and 148 for driving the mechanism (not shown) within the meter 24.

The printing and metering head 12 is enclosed by a housing 150, the latter having a top opening 151 in which the face of the meter 24 is disposed and a front opening 152 which permits the passing of envelopes over the platen 37.

Operation

Envelopes upon which stamps are to be printed are stacked in the hopper 14 of the machine 10 (see Fig. 1) and the motor (not shown) within the housing 13 is energized setting the feeder 15 and conveyor 16 into motion. Envelopes are thus automatically removed, one at a time, from the hopper 14 and delivered by the conveyor 16 to the printing and metering head 12. As the edge of an envelope is carried into the head 12 over the platen 37, the forward end of the envelope contacts a trip (not shown) which stops the conveyor 16 and actuates a clutch (not shown), the latter causing the drive shaft 141 (see Fig. 4) to make one revolution, rotation of the shaft 141 being transmitted to the driven shaft 140 through the coupling 142.

The normal positions of the various elements of the printing head 12 are shown in Figs. 4 and 5, attention being directed to Fig. 5 and particularly to the position of the roller 145 of the crank 143 relative to the cam plate 46 of the printing mechanism 21. As the shaft 140 rotates, the roller

145 rides onto the high point of the cam 46 as shown in Figs. 15 and 16, thus imparting a slight downward movement of the oscillating printing member 36 causing the printing die 44 to be pressed firmly against the inking pad 52 as shown in Fig. 15. As the roller is carried over the high point of the cam 46 in the direction of the arrow of Fig. 16, the oscillating printing member 36 momentarily returns to its uppermost position free from the ink pad 52 as shown in Fig. 4.

During the initial movement of the shaft 140 no movement is transmitted to the oscillating member 50 of the inking mechanism 22 by the cam 146 of the shaft 140 due to the concentricity of the lower portion of this cam as shown in Fig. 17. Continued rotation of the shaft 140 carries the cam 146 to the position shown by dotted lines in Fig. 17, causing the oscillating inking member 50 to be fully depressed as shown in Fig. 18. As the member 50 moves downwardly the pin 62 on the cross-member 60 of the arms 53 rocks the lever 90 about the pin 92 to the position shown in Fig. 18. This motion of the lever 90 is transmitted through the link 93 to the plate 80 causing this plate and the ink pad 52 thereon to be drawn rearwardly along the ways 81 in the arms 53. As the pad 52 moves, as aforesaid, the replaceable element 101 of this pad causes the roller 67 of the tank 65 to roll, thus supplying the ink pad with ink from the tank 65.

While the inking mechanism 22 is being actuated by the cam 146, the printing member 36 is depressed to its printing position by contact of the roller 145 with the cam plate 47 as shown in Figs. 18 and 19. An envelope 155, shown in Fig. 18, is yieldably supported by the platen 37 and gripped thereagainst by serrated faces 200 of the arms 53 as the printing die 44 moves down and is firmly pressed upon the envelope. As the shaft 140 rotates back to its normal position the printing and inking mechanisms are spring-pressed to their normal positions by the aforesaid springs 45 and 56. It will be noted that as the pad 52 returns to its normal position the roller 67 of the ink tank 65 is again rolled over the surface of the pad, thus assuring an adequate supply of ink to the pad.

It will be noted in Fig. 4 that the inking pad 101 is normally in contact with the inking roller 67, and it will be further noted in Fig. 15 that while the die 44 is being inked by the pad 101 the pad is depressed sufficiently to be out of contact with the roller 67. This action allows the roller to play in the cavity 66a as shown in Figs. 9 and 10 resulting in a pumping action which assures an adequate supply of ink from the tank 65 to the roller 67.

When the printing and metering head 12 completes its cycle of operation, the conveyor 16 is set in motion by suitable mechanism (not shown) and the printed envelope is discharged from the head 12. Each rotation of the shaft 140 is transmitted to the meter 24 by the gears 147 and 148, thus registering the amount of postage printed.

It is thus seen that I have provided a very simple and reliable printing press for mailing machines and that the inking mechanism is particularly reliable in assuring an ample, yet properly limited, supply of ink to the printing die. It has been found in actual practice that the apparatus of my invention will operate reliably over long periods with a minimum of attention.

Although I have shown and described but one form of my invention it is to be understood that various changes and modifications might be made

therein without departing from the spirit of the invention or the scope of the following claims:

What I claim is:

1. In a printing press the combination of: a printing member; an inking pad adjacent said member and having a yieldable face; an ink reservoir; ink dispensing means communicating with said reservoir and normally pressurally contacting said pad; and means for bringing said printing member and said pad together and causing said pad face to move away from said ink dispensing means to release the pressure thereagainst, said release of pressure actuating the dispensing means to dispense a quantity of ink from said reservoir. 5
2. In a printing press the combination of: a printing member; an inking pad adjacent said member and having a yieldable face; an ink reservoir, there being an ink dispensing chamber in said reservoir; an ink dispensing member held in a given position in said chamber by pressure of said pad against said ink dispensing member; and means for bringing said printing member and said pad together to cause said pad face to yield, thus causing said ink dispensing member to move to another position in said chamber and feed a quantity of ink from said reservoir whereby it may be applied to said pad. 10
3. A combination as in claim 2 in which said ink dispensing member is a roller. 15
4. A combination as in claim 2 in which said ink dispensing member is a roller and in which said pad moves across said roller and out of the path of said printing member during a printing operation, said movement causing said roller to rotate and transfer ink, fed from said reservoir, onto said pad. 20
5. In a printing press the combination of: a reciprocating printing member; an inking pad disposed beneath said printing member and having a yieldable face; an ink reservoir disposed alongside said printing member; dispensing means receiving ink by gravity from said reservoir into a chamber formed in said means; a roller in said chamber normally resting on said pad; means for bringing said printing member and said pad together to depress said pad face away from said roller, the latter being thereby caused to permit a quantity of ink to flow from said reservoir into said chamber; and means for moving said pad during a printing operation away from said printing member and beneath said roller and in contact therewith whereby the ink which has flowed into said chamber is applied to said pad by said roller. 25
6. In a printing press the combination of: a printing member; an ink transfer member; an ink reservoir; an ink dispenser having a chamber into which ink is adapted to flow from said reservoir, said chamber having a restricted mouth in its lower end; a roller disposed in said chamber and being adapted to close said mouth when free to seat thereon by gravity; and means for bringing said ink transfer member against said roller to reciprocate said roller vertically in said chamber and to rotate said roller while contacting said transfer member, thereby applying ink to the latter. 30
7. A combination as in claim 6 in which said chamber is substantially cylindrical in shape and in which the diameter of said roller is but slightly less than that of said chamber. 35
8. A combination as in claim 6 in which said chamber is substantially cylindrical in shape and in which the diameter of said roller is but slightly less than that of said chamber, and in which communication between said chamber and said reservoir is effected through a passageway opposite said mouth, said roller when engaged by said transfer member being pressed against the entrance to said passageway, thereby substantially closing the same. 40
9. In a printing press the combination of: a printing member; an ink transfer member; an ink reservoir; an ink dispenser having a chamber into which ink is adapted to flow from said reservoir, said chamber having a longitudinally disposed mouth; a roller trapped in said chamber and extending laterally therefrom through said mouth; and means for withdrawing said roller endwise from said chamber. 45
10. In a printing press, the combination of a reciprocating printing member, a relatively flat inking pad in front of said member, a driving means operable for moving said member into inking contact with said pad, thereafter moving said member away from the pad and moving the member into printing relation with an article to be printed, means operable by said driving means for moving said pad from in front of said printing member after the inking contact therewith, an ink reservoir, ink dispensing means communicating with said reservoir and disposed adjacent the path of movement of said pad and normally in contact therewith, and a yieldable face on said pad which yields under pressure from said printing member, thereby moving away from said ink dispensing means, the latter being actuated by this release of pressure thereagainst to dispense a quantity of ink from said reservoir. 50

55. COMMODORE D. RYAN.
